CLAIM

The ornamental design for a band with connector for a wearable device, as shown and described.

DESCRIPTION

FIG. 1 is a top perspective view of a first embodiment of a band with connector for a wearable device showing our new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a back view thereof;

FIG. 8 is a front view thereof;

FIG. 9 is a top perspective view of a second embodiment of a band with connector for a wearable device showing our new design;

FIG. 10 is a bottom perspective view thereof;

FIG. 11 is a top view thereof;

FIG. 12 is a bottom view thereof;

FIG. 13 is a left side view thereof;

FIG. 14 is a right side view thereof;

FIG. 15 is a back view thereof; and,

FIG. 16 is a front view thereof.

The dot-dot-dash break lines on the band portions in FIGS. 1-6 and 9-14 indicate a symbolic break and the appearance of any portion of the band with connector for a wearable device on or between the break lines forms no part of the claimed design.
